UNITED STATES PATENT OFFICE.

PHILLIP EBELING, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A GLASS VESSEL.

43,799.

Specification for Design.

Patented Apr. 1, 1913.

Application filed January 14, 1913. Serial No. 742,052. Term of patent 14 years.

To all whom it may concern:

Be it known that I, PHILLIP EBELING, a citizen of the United States, and residing at Moundsville, in the county of Marshall and State of West Virginia, have invented a certain new, original, and ornamental Design for a Glass Vessel, shown in the accompanying drawings, wherein—

Figure 1 is a side elevation of the vessel, and Fig. 2 a bottom plan view of the same.

I claim:

The ornamental design for a glass vessel, as shown.

PHILLIP EBELING.

Witnesses:

A. C. SCROGGINS, Jr.,
E. M. BOTTOME.
